US00D865543S

(12) **United States Design Patent** (10) **Patent No.:** **US D865,543 S**
(45) **Date of Patent:** **** Nov. 5, 2019**

(54) **WRISTWATCH WITH MONITOR FUNCTION FOR BODY STATE**

(71) Applicant: **Polar Electro Oy**, Kempele (FI)

(72) Inventor: **Lauri Lumme**, Oulu (FI)

(73) Assignee: **Polar Electro Oy**, Kempele (FI)

(**) Term: **15 Years**

(21) Appl. No.: **29/651,481**

(22) Filed: **Aug. 16, 2018**

(30) **Foreign Application Priority Data**

Feb. 16, 2018 (EM) 004710739-0001
